UNITED STATES PATENT OFFICE.

WILLIAM B. WILLIAMS, OF GREENVILLE, SOUTH CAROLINA.

WHIP ROLL FOR LOOMS.

1,414,850.

Specification of Letters Patent. Patented May 2, 1922.

Application filed February 9, 1921. Serial No. 443,555.

To all whom it may concern:

Be it known that I, WILLIAM B. WILLIAMS, a citizen of the United States of America, and a resident of Greenville, 5 county of Greenville, and State of South Carolina, have invented certain new and useful Improvements in Whip Rolls for Looms, of which the following is a full and clear specification.

10 The object of this invention is to provide an improved bearing or journal for the rock-shaft of whip-rolls, and it consists of certain novel features hereinafter described and claimed.

15 In the drawing—

Fig. 1 is a perspective view of one of the bearings of a whip-roll rock-shaft;

Fig. 2 is a side view of the plural-bearing bracket now in common use;

20 Fig. 3 is a vertical longitudinal section through my improved bearing, shown in Fig. 1.

In the drawing, 5 designates the usual rock-shaft carrying the usual whip-roll-arm 25 6 provided with the usual notch-like bearings 7 for the whip-roll rod or roller. The shaft 5 extends through the circular journal hole in a wood block 8 which is fastened to the usual journal bracket 9 by means of 30 a screw 10. This wooden block is desirably impregnated with oil or an oily substance so that oiling of this journal is unnecessary, thereby doing away with the use of a liquid oil, which, even with the utmost care, finds 35 its way to the warp threads of the fabric and thus materially reduces its quality. With my bearing, I have found in actual practice that I not only provide ample lubrication for the shaft, rendering its operation 40 entirely noiseless and practically without wear of the shaft or the bearing-block, but also that I avoid entirely the creation of the fine oily particles that the bearings now in general use produce and 45 deposit on the warp threads.

In my drawing, I have illustrated my device applied to an old, worn structure. In Fig. 2 I have shown by the dotted line 11 and by the full line 11 in Fig. 1 the bearing 50 as worn by the rock-shaft 5. In these views, I have shown this wear to have taken place in the rearmost notch of the series, but it will be understood that it takes place in whatever notch is used, it being of course 55 the custom to journal the rock-shaft in any one of the notches which may be suitable

for the particular cloth being woven. When one of these worn brackets is to be utilized to carry out my invention, I remove the fins 12 which separate the notches, the milling 60 out extending down to the dotted line 13, shown in Fig. 2. This gives me a very desirable bracket 14 for the reception of my wood journal-block 8, since it has an up-standing lip 15 at each end, between which 65 lips the block 8 is fitted, so that the block will be solidly located on the bracket when drawn down on the milled surface 13 by the aforesaid screw 10, the ends of the block fitting against the upstanding lips 15. In 70 this way, I can by a very simple operation on the journal-bracket save the same from going to the junk pile. I can also utilize the old worn rock-shaft 5 by simply turning it half around in the arms 6 (set-screws 16 75 permitting this to be done readily), so as to bring its worn part, shown at 17 in Fig. 1, to the upper side. In this way, I not only completely utilize the old journal bracket and the old rock-shaft, but I produce a bearing 80 for the rock-shaft which is vastly superior to the old bearing in every respect, particularly in that it practically eliminates wear and entirely eliminates the production of the oily particles which fall upon 85 the weft threads and make second quality cloth out of what should be first quality cloth.

The nature and scope of the invention having been thus indicated and its preferred 90 embodiment having been specifically described, what is claimed as new is:

1. In a whip-roll structure for looms, a rock-shaft carrying the whip-roll-arms, a stationary journal-bracket adapted for attachment to the frame of the loom, and an oil-impregnated wood journal-block mounted on the same having a bearing for said rock-shaft. 95

2. In a whip-roll structure for looms, a rock-shaft carrying the whip-roll-arms, a stationary journal-bracket adapted for attachment to the frame of the loom, and an oil-impregnated wood journal-block mounted on the same having a bearing for said 100 rock-shaft, said bearing consisting of a hole extending horizontally through the block. 105

3. In a whip-roll structure for looms, a rock-shaft carrying the whip-roll-arms, a stationary journal-bracket adapted for attachment to the frame of the loom, and an oil-impregnated wood journal-block mount- 110

ed on the same having a bearing for said rock-shaft, said bearing consisting of a hole extending horizontally through the block, said block being removably fastened to the bracket by a removable screw extending up through the bracket and into the block.

4. In a whip-roll structure, a stationary journal-bracket adapted for attachment to the frame of the loom having a horizontal plate and upstanding lips at its ends, a wooden block fitting down on said plate between said upstanding lips, means for fas-

tening the block down on the plate and between the upstanding lips, said block being provided with a journal hole closed except 15 at its ends, and a rock-shaft extending through said hole and carrying the whip-roll-arms.

In testimony whereof I hereunto affix my signature.

WILLIAM B. WILLIAMS.
